UNITED STATES PATENT OFFICE

121,858

DESIGN FOR A RADIO CABINET

Robert Madison Henderson, Fernandina, Fla.

Application December 19, 1938, Serial No. 81,865

Term of patent 7 years

To all whom it may concern:

Be it known that Robert Madison Henderson, a citizen of the United States of America, residing at Fernandina, in the county of Nassau and State of Florida, has invented a new, original, and ornamental Design for a Radio Cabinet, of which the following is a specification, reference being had to the accompanying drawing, forming part thereof.

Figure 1 is a front perspective view of the radio cabinet, and

Figure 2 is a rear perspective view of the radio cabinet.

The characteristic feature of the instant design resides in a radio cabinet having an elliptically shaped solid flat top and bottom, and outwardly bowed abutting narrow panels extending from the edges of the top and bottom and interconnecting same, with a number of the panels missing from the rear and with a number of the panels at the front of the cabinet replaced by a dial and speaker grille, all as shown.

I claim:

The ornamental design for a radio cabinet, as shown and described.

ROBERT MADISON HENDERSON.
